OR D 5,598.

Stoves and Furnaces.

Looking Stoves and Ranges.

D 5598

UNITED STATES PATENT OFFICE.

LEWIS RATHBONE, OF ALBANY, NEW YORK, ASSIGNOR TO JOHN F. RATHBONE & CO., OF SAME PLACE.

DESIGN FOR A COOKING-STOVE.

Specification forming part of Design No. 5,598, dated March 5, 1872.

To all whom it may concern:

Be it known that I, LEWIS RATHBONE, of the city and county of Albany, State of New York, have invented and produced a new and original Design for Cooking-Stoves, of which the following is a specification:

The nature of my design is fully represented in the accompanying photographic illustration, to which reference is made.

In the illustration the newly-designed stove is shown in perspective. The side and front plates of the stove are made with heavy and prominent moldings, and with projecting and heavy molded doors, which give to the stove the appearance of solidity and ornamentation. In each of the oven doors are placed the prominent and heavy-appearing center-pieces, surrounded by the bold and heavy-looking scrolls, as shown. The doors to the combustion-chamber are also, with the center-piece and sur-

rounding scrolls, made with a bold and prominent appearance, corresponding with the center-pieces on the doors of the oven. The front doors, and also the upper sloping piece above, are furnished with the ornamentalations, center-pieces, and bold scrolls corresponding with those before described, as shown in the accompanying illustration. All the several plates and pieces, with their moldings and ornaments shown, are to be used together to form and constitute the general design of the stove.

Having described my invention, what I claim, and desire to secure by Letters Patent, is—

The design of the cook-stove herein described, substantially as shown in the photographic illustration.

Witnesses: LEWIS RATHBONE.
